[57] **CLAIM**

The ornamental design for a balanced back holster, as shown and described.

DESCRIPTION

FIG. 1 is a front elevational view of a balanced back holster showing my new design in its use position on a user shown in phantom lines;

FIG. 2 is a rear elevational view thereof;

FIG. 3 is a top plan view thereof;

FIG. 4 is a bottom plan view thereof;

FIG. 5 is an end view taken in the direction of arrow 5 in FIG. 1; and

FIG. 6 is a view of the opposite end thereof taken in the direction of arrow 6 in FIG. 1.

The broken line showing of user is for illustrative purposes only and forms no part of the claimed design.

FIG. 1

FIG. 6

FIG. 5

FIG. 2
